DESIGN.

W. J. KEEP & C. WIPFLER.

HEATING STOVE.

No. 18,191.

Patented Mar. 20, 1886

UNITED STATES PATENT OFFICE.

WILLIAM J. KEEP AND CHARLES WIPFLER, OF DETROIT, MICHIGAN,
ASSIGNORS TO THE MICHIGAN STOVE COMPANY, OF SAME PLACE.

DESIGN FOR A HEATING-STOVE.

SPECIFICATION forming part of Design No. 18,191, dated March 20, 1888.

Application filed June 9, 1887. Serial No. 240,831. Term of patent 7 years.

To all whom it may concern:

Be it known that we, WILLIAM J. KEEP and CHARLES WIPFLER, citizens of the United States of America, residing at Detroit, in the 5 county of Wayne and State of Michigan, have invented a certain new and original Design for Stoves, of which the following is a specification, reference being had therein to the accompanying drawing.

10 This design is more particularly adapted for use in air-heating stoves.

Referring to the photograph appended hereto, A represents the cylinder of the stove, and B is the door-frame thereof, having projecting 15 columns b on each side and a molding, b', at top. The upper door, C, has a series of openings, between which are columns ornamented by rosettes and scrolls. The lower door, C', is divided into two sections by horizontal beads, 20 the upper section being ornamented with a shield and partially surrounded by scrolls. The lower section is provided with three openings surrounded by crossed scrolls. Below the cylinder and door-frame is a pot-ring, D, 25 ornamented with beads and projecting portions d under each side of the door-frame. Underneath the pot-ring is the pot E, which is ornamented by fluting, except at the points beneath the sides of the door-frame, where there 30 are projecting columns e e. The pot rests on the ash-pit top F, which is ornamented with scroll-work, but has its lower part plain. Each of the legs G has its upper part ornamented with a rosette and a corona partly surrounding 35 said leaf. The lower part of the leg is plain, with the exception of the toe, which is turned outward in the form of a scroll. The two front legs have each one straight side uniting with the ash-pit door H, to give the appearance of 40 a base. The ash-pit door H has three openings, behind which appears the damper-slide h, ornamented with rosettes filling the opening in the door. The surface of the door is ornamented by scrolls, which pass over the top of 45 the center opening, around the side openings, and then divide into two branches, one of which curls upward and the other crosses the main lines of the scroll and curls underneath the same. Above the openings is a projecting 50 poke-door, h', which from its position appears to form a part of the lower portion of the ash-

pit top. Surrounding the pot, and supported by the standards I upon the ash-pit top, is a ring, J. Each standard has an expanded top ornamented with scroll-work, forming an ornament to the ring J. 55

The top of the stove consists of a fixed side ring, K, and a cover, L, carrying a vase, M. The top K is ornamented by a series of small moldings, k k', and its convex upper part is 60 covered with scroll-work composed of fine lines, some of which pass over some of the lines of the other scrolls and under others. The cover L is ornamented by a plain base-ring, l, and scroll-work, the ends of the scrolls inclosing or 65 terminating in rosettes. The vase M has a base, m, and a bowl, m', consisting of a convex curved bottom, above which is a beveled portion, a projecting rim, and a roughened perpendicular portion, above which is a series of 70 circular beads of gradually-decreasing size, a plain convex-curved portion, then a projecting molding, above which is a fluted dome-shaped top surmounted by a knob.

The leading features of this design reside, in 75 addition to the novel shape and ornamentation of the stove as an entirety, in the peculiar shape and ornamentation of the segregable parts thereof, as above described, shown in the photograph, and specified in the following claims. 80

What we claim as new is—

1. The design for a stove herein shown and described, consisting of the vase M, cover L, top K, the cylinder A, having a door-frame with columnar projections b, doors C C', the 85 pot-ring D, having corresponding projections, the pot E, provided with columns corresponding to the projections on the pot-ring, the ash-pit top F, and the legs G, all having the shape substantially as shown. 90

2. In a design for a stove, an urn having a base, m, a bowl, m', provided with a convex-curved bottom, a beveled portion, a roughened perpendicular side, a series of circular beads of gradually-decreasing size, a plain convex-curved portion, a projecting molding, a fluted dome-shaped top, and a knob, as shown and described. 95

3. In a design for a stove, a foot-ring, J, provided with T-shaped standards I, having their 100 upper ends ornamented with scrolls, as shown.

4. In a design for a stove, the body herein

shown and described, consisting of the cylinder A, having a projecting columnar door-frame, the pot-ring D, having projections *d*, corresponding to the projecting door-frame, and a pot, E, having columns under the projections *d*, all having the shape substantially as shown.

5. In a design for a stove, a top consisting of the adjacent moldings *k k'*, curved on their upper edges, and the adjacent curved portion beneath the cover ornamented with scroll-work consisting of a series of scrolls, each starting from a scroll from which extend lines, some of which terminate in an upwardly-extended scroll turned to the left and others in a scroll turned down and to the right, and a single convolute across said lines and terminating between the first-mentioned scroll and the scroll turned to the left, as shown.
10. In a design for a stove, a door-frame ornamented with columnar projections, with a projecting apertured connecting-piece at the top running from one column to the other, as shown.
15. 6. In a design for a stove, a plain cylinder surmounting a pot-ring and ornamented with a rectangular door-frame having columnar projections each side of the door, extending to the
20. 7. In a design for a stove, a plain cylinder surmounting a pot-ring and ornamented with a rectangular door-frame having columnar projections each side of the door, extending to the

pot-ring and appearing to rest on projections thereon, and a molded top having perforations 30 above the molding, as shown and described.

8. In a design for a stove, a fire-pot ornamented with vertical flutes and the vertical projecting columns *e e*, and surmounted by an overhanging pot-ring curved outwardly over 35 said columns, as shown.

9. In a design for a stove, an ash-pit door having as a surface ornamentation a plain upper overhanging band having upon its outer face an outwardly-projecting door, *h'*, as shown. 40

10. In a design for a stove, a leg having a rosette, a corona beneath the same, and terminating in a scroll-shaped toe, as shown.

11. In a design for a stove, the upper fire-door having openings, between which are columns ornamented by rosettes and scrolls above and below said rosettes, as shown. 45

In testimony whereof we affix our signatures, in presence of two witnesses, this 6th day of June, 1887.

WILLIAM J. KEEP.
CHARLES WIPFLER.
